UNITED STATES PATENT OFFICE.

MARION ROBINSON, OF PRINCETON, WEST VIRGINIA, ASSIGNOR OF ONE-HALF TO
MRS. LOUISA MARKLAND, OF JENKINS, KENTUCKY.

RAILROAD SWITCH.

Application filed May 12, 1922. Serial No. 560,319.

To all whom it may concern:

Be it known that MARION ROBINSON, a citizen of the United States of America, residing at Princeton, in the county of Mercer 5 and State of West Virginia, has invented new and useful Improvements in Railroad Switches, of which the following is a specification.

The object of the invention is to provide 10 a simple and efficient switch for actuation by the rolling stock or by mechanism carried by the rolling stock for use particularly in connection with sidings and adapted to be employed in reference to trackage designed 15 for mine cars and the like as a means of adapting each car as it approaches the main line to close the switch permitting passage on to the main line and the resetting of the switch to open the main line for use by 20 other cars traversing the track; and with this general object in view the invention consists in a construction and combination of parts of which a preferred embodiment is shown in the accompanying drawings, 25 wherein:

Figure 1 is a plan view of a portion of a track having a switch mechanism embodying the invention arranged in operative relation therewith.

30 Figure 2 is a side view of the switch mechanism as applied and showing in connection therewith a car carried actuating device for use in setting the same.

Figure 3 is a detail in perspective of the 35 rocker by which motion is communicated to the switch rails.

Figure 4 is a similar view of one of the trips.

Figure 5 is a similar view of a trip actuator 40 adapted to be carried by the rolling stock.

Figure 6 is a detail in perspective of the actuator.

The trackage illustrated in the drawing 45 includes the main line rails or sections 10, the siding rails 11 and pivotal switch rails 12 for respective and alternate arrangement in operative relation with the main rails to either open the main track or open 50 the siding. The switch rails are connected by a switch bar 13 having connection with a radial arm 14 of a rocker 15 mounted in a suitable bracket 16 adjacent to the track as for example upon one of the cross ties 17, and 55 the other arms 18 of said rocker are respec-

tively connected by rods 19 or the equivalents thereof with trips 20 pivotally mounted on suitable brackets 21 adjacent to a siding rail within the switch and adjacent to a main line rail outside of the switch. These 60 trips are pivotally mounted as indicated at 22 for movement in a common direction to respectively open the siding and open the main line so that a car coming out of the siding on to the main line which actuates the trip within the siding as it approaches the switch rails serves to set the switch rails to connect the siding with the main track, and as the car progresses for a further operating means or a further operation of the same 65 operating means is caused to engage the trip outside of or beyond the siding to move the trip in the same direction as the car, the switch rails will be reset to open the main 70 line and close the switch.

In the construction illustrated the means provided for this alternate actuation in a common direction of the switch actuating trips consists of a plunger rod 23 yieldingly held in an elevated or inoperative position by a spring 24 and mounted in a tubular guide 25 which as indicated in Figure 2 may be secured to the car 26 in a suitable or convenient position with adequate bracing means indicated at 27, and an operating or hand lever 28 fulcrumed as at 29 and having connection with said plunger as indicated in Figure 5 by the arrangement of its terminal in a suitable opening 30 of the plunger rod. The latter also preferably carries 90 at its lower end an anti-friction roll 31 for contact with the beveled surfaces 32 of the trip. It will be understood that in entering a siding a car equipped with a suitable actuating device such as that herein described and illustrated in Figures 5 and 6 may be caused to first open the switch to permit of entering the siding and then of closing the siding to open the main line by a reverse movement of the switch tongues through 95 successive movements in the same direction of the trips but in the opposite direction to that required in leaving or passing out of the siding.

Furthermore as a means of maintaining 105 the switch members in their set positions to open either the main line or the siding each trip which is pivoted as above indicated at 22 is extended to form a rock arm 33 carrying an anti-friction roll 34 for traversing a 110

bowed spring 35 secured in any suitable or convenient manner to the ties or other convenient objects in such a position that the roller of the rock arm traverses the spring 5 and is impelled by the latter to yieldingly hold the trip in either of its terminal or set positions and to continue the shifting movement of the trip in either direction to the end of its movement in that direction to thus 10 serve as a full stroke controlling means, to the end that the switch may not be left in a half open or half closed position subject to engagement with the wheels and liable in practice to cause derailment or injury to the 15 trackage.

Having described the invention, what is claimed as new and useful is:—

1. A switch mechanism for controlling the communication between a siding and the 20 main line and including movable switch rails, having a rocker operatively connected with the switch rails for alternately positioning them in operative relation with opposite track rails and trips operatively connected with the rocker and located adjacent to the track rails respectively inside and outside of the siding for actuation in a common direction corresponding with the direction of movement of a car, for shifting the 25 switch rails successively in opposite directions, each trip being provided with a beveled contact terminal and full stroke mechanism connected therewith for holding the trip alternately in its set positions. 30

35 2. A switch mechanism for controlling the communication between a siding and the main line and including movable switch

rails, having a rocker operatively connected with the switch rails for alternately positioning them in operative relation with opposite track rails and trips operatively connected with the rocker and located adjacent to the track rails respectively inside and outside of the siding for actuation in a common direction corresponding with the direction of movement of a car, for shifting the switch rails successively in opposite directions, each trip being provided with a rocker arm arranged in operative relation with a bowed spring for locking the same in its adjusted positions and impelling the rocker from an intermediate to its terminal position. 40 45 50

3. A switch mechanism for controlling the communication between a siding and the main line and including movable switch rails, a rocker, means for actuating said switch rails for alternately positioning them in operative relation with opposite track rails, trips operatively connected with said means and located adjacent to the track rails respectively inside and outside of the siding for actuation in a common direction corresponding with the direction of movement of a car for shifting the switch rails successively in opposite directions, said trips being adapted for operation by a train carried actuator, and means engaged by the trips to complete their movements to terminal positions after said actuator has shifted them to intermediate positions. 55 60 65 70 75

In testimony whereof he affixes his signature.

MARION ROBINSON.
